United States Patent Office.

BERNHARD D. BEIDERHASE, OF NEW YORK, N. Y.

Design No. 4,382, dated October 4, 1870.

DESIGN FOR SPOON AND FORK-HANDLES.

The Schedule referred to in these Letters Patent and making part of the same.

To all whom it may concern:

Be it known that I, BERNHARD D. BEIDERHASE, of the city of New York, in the county and State of New York, have invented a new and original Design for Spoon and Fork-Handles; and I do hereby declare that the following is a full, clear, and exact description thereof, which will enable others skilled in the art to make and use the same, reference being had to the accompanying drawing forming part of this specification.

The nature of my design is fully represented in the accompanying drawing, to which reference is made.

Figure 1 is a front view.

Figure 2 is a back view.
Figure 3 is a section on the line $x\ x$.
Figure 4 is a cross section on the line $y\ y$.
Similar letters of reference indicate corresponding parts.

I claim as my invention—
The design for the handles of spoons, forks, &c., as shown.

BERNHARD D. BEIDERHASE.
